BUILT-IN OVEN

Charles T. Waltman, Lake Forest, Ill., assignor to Magic Chef, Inc., Cleveland, Tenn.

Filed Aug. 26, 1964, Ser. No. 81,459

Term of patent 14 years

(Cl. D81—26)

Fig. 1.

Fig. 2.

Fig. 3.

FIG. 1 is a perspective view of a built-in oven, showing my new design;

FIG. 2 is a front elevation thereof; and

FIG. 3 is a side view thereof.

The back, top, bottom and sides are essentially flat surfaces. The wall shown in broken lines in FIG. 3 is included for illustrative purposes only.

I claim:

The ornamental design for a built-in oven, as shown and described.
